SOUND RECORDING SYSTEM

Irl M. Chambers, Los Angeles, Calif., assignor, by
mesne assignments, to Western Electric Com-
pany, Incorporated, a corporation of New York

Application September 15, 1932, Serial No. 633,263

10 Claims. (Cl. 179—100.3)

This invention relates to recording systems and particularly to systems for recording modulated currents on a photographic medium.

The object of the invention is a system for recording modulated currents in which a greater range of amplitudes of the modulated currents may be recorded than may be recorded by known systems.

A feature of the invention resides in the method of separately recording the half-waves of the variations in amplitude of the modulated currents to form separate records. As each half-wave may be permitted to vary over the whole available part of the characteristic of the recording medium, a greater range of amplitudes may be recorded.

Another feature of the invention resides in the method of recording each half-wave, so that when the amplitude of a half-wave is very small, the mean exposure of the photographic medium is at the lower end of the region of correct exposure for the photographic medium. For waves of small amplitude, a very light negative record will result, and this negative record, when printed, will produce a dense positive record. The currents due to irregularities in the optical structure of the positive record, which are produced during the reproduction of the record, will thus be reduced. A reduction in these noise currents will permit modulated currents of less than the present minimum amplitude to be recorded, thus the range of amplitude which may be recorded is further increased.

A further feature of the invention resides in a novel form of light valve, in which two stretched ribbons are alternately displaced to form separate records of the half-waves of the variations in amplitude of the modulated currents.

A developed photographic impression may be measured by permitting a known intensity of light to fall on the impression and measuring the intensity of the light transmitted through the impression. The ratio of the original intensity of the light divided by the intensity transmitted through the impression is known as the opacity. The logarithm of the opacity is known as the density. The exposure of a photographic medium, or the light energy affecting the medium, is approximately equal to the intensity of the light impressed on the medium multiplied by the time during which the medium is exposed to that intensity of light.

Let a photographic medium be exposed to a graduated series of exposures, then developed and the densities produced by the various values of

exposures measured. The densities may then be plotted against the logarithms of the relative exposures to produce the well known Hurter and Driffield curve of the medium.

If the H and D curve of a photographic medium is examined, it will be found that the density of the impression produced is not linearly proportional to the logarithm of the exposure when the exposure is small. This range of the characteristic is known as the region of under-exposure. At a fairly definite point, the curve becomes straight and the density of the impression produced is linearly proportional to logarithm of the exposure. This range of the characteristic is known as the region of correct exposure. Above a certain value of exposure, the curve again bends and the densities are no longer linearly proportional to the exposures. This range of the characteristic is known as the region of over-exposure.

In the known method of sound recording by the so-called variable density method, in the absence of modulated currents the exposure of the medium is adjusted to produce a density in the center of the region of correct exposure. The modulated currents then actuate the recording device and cause the exposure to vary above and below this value. The maximum amplitude of the variations of the modulated currents which can be recorded without distortion, will be that amplitude which causes the exposure to vary over the whole region of correct exposure. That is, one half wave of the variation will cause the exposure to increase from the center point up to the point where the region of over-exposure commences and then to decrease back to the center point. The other half wave of the variation will then cause the exposure to decrease from the center point down to the point where the region of under-exposure commences and then to increase back to the center point. Thus, each half wave may cause the exposure to vary over one-half of the region of correct exposure.

In the present invention, separate records are employed for the two half waves of the variations. In the absence of modulated currents, the exposure of the medium of both records is adjusted to produce a density at the lower end of the region of correct exposure. When a half wave of the modulated currents actuates the recording device, the exposure of the first record is virtually unchanged while the exposure of the second record is increased. The maximum amplitude of the variations of the modulated currents which can be recorded without distortion

will cause the exposure of the second record to vary over the whole region of correct exposure. That is, the half wave causes a variation over the whole region. Similarly, when the other half wave of the modulated currents actuates the recording device, the exposure of the second record is virtually unchanged and produces a density at the lower end of the region of correct exposure, while the exposure of the first record is increased. Thus, each half-wave may cause the exposure to vary over the whole region of correct exposure. That is, the amplitude of the variations of the modulated currents which may be recorded without distortion is approximately double the amplitude which may be recorded by present methods.

Recent experiments have shown that the noise currents due to irregularities in the photograph record produced during reproduction are approximately proportional to the average transmission of the positive record. If the photographic processes are controlled so that no overall distortion is produced, the transmission of the positive record is proportional to the exposure of the negative record. As hereinabove described, in known methods of sound recording, the mean value of the exposure is adjusted to be in the center of the region of correct exposure. The noise currents produced in reproduction are thus comparatively large. In the present invention, the exposure for currents of small amplitude is at the lower end of the region of correct exposure and is thus comparatively small. The noise currents are correspondingly small. Thus, modulated currents of smaller amplitude may be recorded and still be distinguishable above the noise currents. The range of amplitudes which may be recorded is thus extended due to the reduction in the absolute magnitude of the noise currents.

In a preferred embodiment of the invention, a light valve, comprising two flat parallel ribbons immersed in a constant magnetic field, is employed. The ribbons are stretched between insulating supports disposed near the outer ends of the ribbons. A central conductive bridge at the center of the ribbons forms an electrical connection between the ribbons. Separate apertures in front of a moving photographic film are aligned with the centers of the two portions of the ribbons and are illuminated by a suitable source of light. The ribbons are mechanically adjusted so that they normally close the apertures to such an extent that the resultant exposure will be at the lower end of the region of correct exposure. Modulated currents are supplied to one end of one ribbon, flow through half of that ribbon, through the conductive bridge, through half of the other ribbon and out of the end of the second ribbon distant from the point of supply. The reaction of the magnetic field formed by the modulated currents and the steady magnetic field cause the half ribbons to vibrate and alternately increase the light passing through the apertures.

In the drawing:

Fig. 1 diagrammatically shows a sound recording system embodying the invention;

Fig. 2 is a partial sectional view of one form of light valve;

Fig. 3 is an enlarged view of the pole pieces, bridge and ribbons of the valve shown in Fig. 2;

Fig. 4 is a partial sectional view of another form of light valve;

Fig. 5 is an enlarged view of the pole pieces and ribbons of the valve shown in Fig. 4.

The details of the mechanical assembly and arrangement of the light valves shown in Figs. 2, 3, 4 and 5 may be similar to the light valve disclosed in U. S. Patent 1,638,555 issued August 9, 1927 to E. C. Wente. Thus, it is not necessary to complicate the present drawing by showing the minor mechanical details of the suspension and tensioning of the light valve ribbons.

Acoustic waves are detected by a microphone 1 and produce a modulated current which is amplified in the amplifier 2. The modulated current may be further amplified, if desired, in the amplifiers 3 and 4. The amplified currents are applied through wires 5, 7 to the ribbons 6, 8 of the light valve.

Light from a suitable source 9 is focussed by a lens system 10 on apertures 12, 13 pierced in the pole pieces of a permanent magnet 11. The light passing through the apertures 12, 13 is partially cut off by the ribbons 6, 8 of the light valve. The light emerging from the apertures 12, 13 is focussed by a lens system 14 to form two images 15, 16 on a photographic film 17 moved at constant speed through the light beam in the usual manner.

The ribbons 6, 8 of the light valve shown in Figs. 2 and 3 are secured at their center to a conductive bridge 18. As clearly shown in Fig. 2, the ribbons 6 and 8 are in two planes displaced from each other so that if the ribbons are displaced past the center line they will not meet but will overlap, ribbon 8 oscillating behind ribbon 6.

In Fig. 3 the lower edge of ribbon 6 is preferably aligned with the upper edge of the aperture 13 while the upper edge of ribbon 8 is aligned with the lower edge of aperture 12. In the position of rest, the ribbons 6 and 8 are thus preferably spaced apart by a small distance. This distance may be arranged so that the light impressed on the sensitive film, when the light valve is in a position of rest, is just sufficient to produce an exposure at the lower end of the region of correct exposure of the emulsion used.

The modulated currents from wire 5 flow along ribbon 6 to the bridge 18 then along ribbon 8 to the wire 7 back to the amplifier 4. The right hand portion of ribbon 6 and the left hand portion of ribbon 8 do not carry any current. Due to the reaction between the magnetic field formed by the modulated currents flowing in the ribbons and the steady magnetic field due to the magnet 11, the ribbons will be displaced. Assume that a half wave of the modulated currents causes the left hand portion of ribbon 6 and the right hand portion of ribbon 8 to move upward. The remaining portions of the ribbons do not carry any current and will not be displaced. Ribbon 6 will uncover a greater part of the aperture 12 and the exposure of the record 15 will increase. Ribbon 8 will pass under ribbon 6 and the exposure of record 16 will decrease slightly and then remain unexposed. The half wave of modulated current then decreases to zero and the ribbons are restored to the position of rest. Ribbon 6 has thus produced on record 15, a record of the first half wave of the modulated current while record 16 has at all times been virtually unexposed. The next half wave of the modulated current causes ribbons 6 and 8 to be displaced downward. Ribbon 8 will uncover an increasing part of aperture 13 and the exposure of record 16 will increase while ribbon 6 will pass in front of ribbon 8 causing the exposure of record 15 to decrease slightly and then remain unexposed. When the second half wave of the modulated current de-

creases to zero, both ribbons are restored to the position of rest. Thus, the full range of the characteristic of the emulsion used may be used to record a half wave of the modulated current and the volume of the recorded sound may be doubled. At the same time, the exposure applied to the negative film is at all times a minimum, thus the undesired noises produced during reproduction of a positive print of the negative record will also be a minimum.

In Fig. 5, current from the amplifier 4 flows through wire 5, to conductive connector 21, through ribbons 19 and 20 in parallel to conductive connector 22, wire 7 back to the amplifier 4. The wires 19 and 20 may be spaced so that in their position of rest the exposure produced on the negative film is at the lower end of the region of correct exposure. When the first half wave of modulated current is applied, assume both ribbons move upward. Ribbon 20 will uncover aperture 13 and the exposure of record 16 will be varied while aperture 12 is covered and record 15 is unexposed. On the second half wave of modulated current, both ribbons will move downward from the position of rest, aperture 12 will be uncovered, the exposure of record 15 will be varied, while aperture 13 is covered and record 16 is unexposed. In the type of valve shown in Figs. 4 and 5 the overlapping of ribbons 19 and 20 is not essential, but renders the adjustment of the ribbons easier. The apertures 12 and 13 are also displaced slightly vertically from the position of the apertures 12 and 13 in Fig. 3.

What is claimed is:

1. A light valve comprising a magnetic structure having parallel pole faces each pierced by a plurality of aligned apertures, a pair of electrical conductors supported between said parallel pole faces and defining a light transmitting slot in each of said apertures, an electrically conductive connection between said conductors intermediate their ends, and means for supplying current to one end of one of said conductors and to the other end of the other of said conductors to vary their space relation whereby the light transmitted through said slots is alternately varied in accordance with the variations in the alternate half-waves of the current.

2. A light valve comprising parallel magnet having aligned pole faces each pierced by a pair of aligned apertures, an electrical conductor supported between said parallel pole faces and defining a light transmitting slot in each of said apertures, and means for supplying modulated current to said conductor to displace said conductor whereby the light transmitting slots in said apertures are alternately varied in accordance with the variations in the alternate half-waves of the current.

3. A recording device comprising a photographic film moved at constant speed, means for projecting light on said film, a light valve interposed between said means and said film, said valve comprising a magnetic structure pierced by a pair of apertures defining said light into two separate beams and a member supported by said structure to define the beam of light transmitted through each of said apertures, and electrically operated means to vary the space relation of said member whereby the beams of light transmitted through said apertures are alternately varied in accordance with the variations in the alternate half waves of the electric current.

4. A light valve comprising a magnetic struc-

ture having parallel pole faces each pierced by two apertures, an electrical conductor supported between said pole faces with one edge aligned with the upper edge of one of said apertures, and substantially closing the second of said apertures, a second electrical conductor supported between said pole faces with one edge aligned with the lower edge of the other of said apertures and substantially closing the first of said apertures, an electrical connection between said conductors, and means for supplying current to one end of the first conductor and the other end of the second conductor to cause said conductors to alternately open said apertures in accordance with the alternate half waves of the current.

5. A light valve comprising a magnetic structure having parallel pole faces each pierced by two apertures, an electrical conductor supported between said pole faces with one edge aligned with the upper edge of one of said apertures and substantially closing the second of said apertures, a second electrical conductor supported between said pole faces with one edge aligned with the lower edge of the other of said apertures and substantially closing the first of said apertures, an electrical connection between said conductors intermediate their extremities, and means for supplying current to one end of the first conductor and the other end of the second conductor to cause said conductors to alternately open said apertures in accordance with the alternate half waves of the current.

6. A light valve comprising a magnetic structure having parallel pole faces each pierced by two apertures, the lower edge of the first aperture being approximately aligned with the upper edge of the second aperture, an electrical conductor supported between said pole faces with one edge aligned with the upper edge of the second aperture, a second electrical conductor supported between said pole faces with one edge aligned with the lower edge of the first aperture, a conductive bridge retaining said conductors in different planes, and a circuit for supplying current to one end of the first conductor and the other end of the second conductor to cause said conductors to alternately open said apertures in accordance with the alternate half waves of the current.

7. In a recording system, a source of light, a photographic film moved at constant speed, means for projecting light from said source on said film including a magnet having parallel pole faces each pierced by apertures defining two beams of light, an electrical conductor supported by said magnet in one plane, and obturating one of said beams, a second electrical conductor supported by said magnet in another plane and obturating the other of said beams, said conductors being electrically connected, a source of signal currents, and a circuit for conveying signal currents to one end of said first conductor and the other end of the second conductor to cause said conductors to alternately expose said beams in accordance with the alternate half waves of the signal currents.

8. In a recording system, a source of light, a photographic film moved at constant speed, means for projecting light from said source on said film including a magnet having parallel pole faces each pierced by apertures defining two beams of light, each beam having sufficient intensity to cause complete exposure of said film, an electrical conductor supported by said magnet and normally obturating one of said beams

- to produce an exposure of said film at the lower end of the region of correct exposure, a second electrical conductor supported by said magnet and normally obturating the other of said beams
- 5 to produce an exposure of said film at the lower end of the region of correct exposure, and means for applying signal currents to said conductors whereby said beams are alternately varied in accordance with the alternate half waves of said
- 10 currents.
9. The method of recording the variations in an electrical current which comprises projecting two beams of light uniformly over the full width of two different portions of a uniformly moving
- 15 light sensitive medium, adjusting the minimum exposures of both said portions to a predetermined small value, increasing the exposure uniformly over the full width of one portion of said medium in accordance with an increase in the
- 20 current flowing in one direction, alternately increasing the exposure uniformly over the full width of the other portion of said medium in ac-

cordance with an increase in the current flowing in the opposite direction and developing said medium.

10. The method of recording the variations in an electrical current which comprises projecting 5 two beams of light uniformly over the full width of two different portions of a uniformly moving light sensitive medium, adjusting the minimum exposures of both said portions to be at the lower end of the region of correct exposure of the medium, adjusting the maximum exposures of both 10 said portions to be within the region of correct exposure of the medium, increasing the exposure uniformly over the full width of one portion of 15 said medium in accordance with an increase in the current flowing in one direction, alternately increasing the exposure uniformly over the full width of the other portion of said medium in accordance with an increase in the current flowing 20 in the opposite direction and developing said medium.
